UNITED STATES PATENT OFFICE.

CHARLES FOSTER BLADES, OF TOPEKA, KANSAS.

PERMUTATION LOCK.

Application filed October 30, 1923. Serial No. 671,721.

This invention relates to permutation locks and has for its object the provision of a device for locking a safe and which is simple in construction and easy of manipulation when the combination by which the lock is operated is known.

A further object of the invention is the provision of a device which does not require the use of a key or tumblers and which is absolutely noiseless in operation so that it would be impossible for an unauthorized person to obtain the combination by sounds within the lock when experimenting with the visible operating elements.

This invention will be best understood from a consideration of the following detailed description, in view of the accompanying drawing forming a part of the specification; nevertheless it is to be understood that the invention is not confined to the disclosure, being susceptible of such changes and modifications which shall define no material departure from the salient features of the invention as expressed in the appended claims.

In the drawings:

Figure 1 is a plan view of the operating mechanism for locking the bolt.

Figure 2 is a horizontal section of the same.

Figure 3 is a side view of the same.

Figure 4 is an end view of the operating mechanism.

Figure 5 is a view in perspective of one of the rotatable members and the braking means for said rotatable member.

Figure 6 is a view in perspective of the lock bolt and cooperating mechanism for permitting and causing shifting of the same.

Referring more particularly to the drawings, 1 designates the usual lock bolt which is adapted to be locked against reciprocation by a pivoted latch 2.

The permutation lock per se comprises a pair of upper and lower base plates 3 and 4 which are secured together and spaced from each other by posts 5. A shaft 6 is mounted centrally of the base plates and has its opposite ends in bearings in said plates. A gear 7 is rigidly connected with the shaft 6 and is in mesh with a spur gear 8.

The gear 8 is rigidly mounted on a shaft 9. Said shaft has one end mounted in a bearing in the plate 3 and its opposite end projects beyond the base plate 4 and is mounted for rotation in a bearing in the

base plate 4. A resilient spider 10 connected with the shaft 9 on the inner face of the base plate 4 has the ends of its legs in engagement with the inner wall of said plate. A hub 11 is rigidly connected with the projecting end of the shaft 9 and is provided with three arms 12, 13 and 14. The arm 14 is provided with an operating handle 15 for rotating the shaft 9. A pin 16 is rigidly connected with the outer wall of the base plate 4 and with which the operating handle 15 is adapted to be alined at certain times. The pin is spaced beyond the operating circumference of said handle.

Loosely mounted on shaft 6 and spaced from each others are three discs 17, 18 and 19. These discs are made of fiber or some non-metallic material and have a friction tight engagement with the metal discs 20 whereby the fiber discs may be angularly displaced relative to the metal discs for changing the combination of the lock.

Resilient webs 21 engage the washers 22 mounted respectively on the three discs, while the outer free ends of the legs of the webs are in engagement with the outer surface of the non-metallic discs.

A collar 23 spaces the metal disc 20 attached to the disc 17 from gear 7, while a resilient web 24 in engagement with a washer 22, spaces the non-metallic disc 19 from the inner wall of the base plate 4.

A post 25 has its opposite ends rigidly connected with the base plates 3 and 4 and is located adjacent the peripheries of the non-metallic discs and is provided with spaced bearings adapted to receive the coiled portions 26 of the resilient arms 27, 28 and 29. The inner ends of these resilient arms are provided with brake shoes 30 adapted to engage at certain times the outer peripheries of the adjacent non-metallic discs 17, 18 and 19.

Rigidly connected on a shaft 31 are spaced cam members 32, 33 and 34 adapted to be engaged by the free ends 35 of the respective resilient members 27, 28 and 29.

Cam member 32 is provided with an arcuate face in which is formed a groove 36. The opposite faces 37 and 38 are straight and are at right angles to each other. Cam member 33 is provided with two parallel straight faces 39 and 40 and two curved end faces having grooves 41 and 42. Cam member 34 is similar to cam 32 and is provided with an arcuately shaped periphery in

which is formed a groove 43. The other two faces 44 and 45 are straight and are at right angles to each other.

The shaft 31 projects beyond the base plate 4 and is provided with an operating handle 46 whereby the shaft is rotated while the face of the base plate 4 is provided with notches 47, 48, 49 and 50 located on the circumference of a circle and at the ends of the vertical and horizontal diameters of the circle and which are at right angles to each other. These notches are respectively numbered 1, 2, 3 and 4. The crank arm 46 is provided on its under face with a projection 51 adapted to engage the notches 47, 48, 49 and 50 when the crank arm is operated.

The disc 17 is provided with a notch 52 adapted to aline with a notch 53 in disc 18 and a notch 54 in disc 19 whereby the lugs 55 on the latch 2 will fall within said alined notches so that its free end 56 may be thrown out of engagement with the lug 57. At this time the lock bolt 1 may be operated for releasing it from its keeper to open the safe door.

An operating handle 61 rigidly connected with a shaft 62 rocks said shaft, oscillating a link 63 mounted on said shaft and pivotally connected at 64 to the latch bar 2 adjacent its inner end 56. A lever 65 rigidly connected to shaft 62 is provided with a pin 66 operating in a groove (not shown) in bolt 1 so that rocking of shaft 62 not only raises latch 2 but causes a sliding movement of bolt 1.

A post 58 is mounted upon the base plate 4 and has its inner end located adjacent the periphery of the metal discs 20. Each one of the discs 20 is provided with a lug 59 which is adapted to engage the post and prevent rotation of the metallic and non-metallic discs in one direction. As shown in Figure 1 the notches 52, 53 and 54 are adapted to be alined at the point marked 60 on the plate 4.

The operation of my device is as follows:

As long as the lugs 55 on latch 2 are in engagement with the peripheries of the non-metallic discs 17, 18 and 19, the outer end 56 of said latch will be maintained in engagement with the lug 57 on bolt 1 and thereby prevent operation of said bolt. When the three discs are so alined that their respective notches 52, 53 and 54 are alined at the point 60 in Figure 1, the lugs 55 on latch 2 will drop into the alined notches and release the end 56 from the lug 57 on bolt 1 when handle 61 is operated. In order to aline the notches it is necessary to rotate the crank arm 46 until the lug 51 on said arm drops within the notch marked #4 on base plate 4 of Figure 1. At this time the flat faces of the cam members, as shown in Figures 2 and 5, will be so positioned that they will engage the ends 35 of the respective

resilient members 27, 28 and 29. At this time the brake shoes 30 of the resilient arms will be thrown out of engagement with the peripheries of the discs 17, 18 and 19 and permit all three discs to be rotated at one time. The crank arm 14 through the handle 15 is rotated in an anti-clockwise direction for five or six turns whereby the lugs 59 on the metal disc 20 will be moved into engagement with the post 58. The crank arm 14 is continued in this rotation until it alines with pin 16. Crank arm 46 is then moved until the lug on said arm engages notch 47. The cam members 34 and 41 are so arranged that the active portion of the cam which is provided with grooves will engage the ends 35 of the resilient arms 28 and 29 and force the shoes 30 of said arms into engagement with the discs 18 and 19 and prevent rotation of said discs. The crank arm 14 is then rotated in a clockwise direction until the arm 14 makes a complete revolution and passes pin 16 and arm 13 is alined with said pin. The arms 12, 13 and 14 form angles of 120° with each other so that the angular revolution of arm 14 would be 480°. Each 120° I term a space so that the arm 14 would be rotated through four spaces.

Lever 46 is then moved to notch #2 and arm 14 is turned anti-clockwise until it alines with pin 16. The arm 14 is again operated through an angular displacement of 840° or 7 spaces. Crank arm 46 is then moved to notch 3 and arm 14 is again rotated anti-clockwise to aline with pin 16. This arm is then rotated clockwise through 1320° or through eleven spaces.

By the three separate operations of angular movement of the arm 14 the three notches 52, 53 and 54 are alined at the point marked 60 in Figure 1 whence the lugs 55 on the arm 2 may remove into these notches and release the end 56 of said arm from lug 57 on lock bolt 1 as the lock bolt is shifted for opening the door of the safe by actuation of handle 61.

At the first operation of arm 46 to notch 47 together with the angular displacement of the arm 14 through four spaces, notch 52 was brought to point 60 in Figure 1. The movement of arm 46 causes one of the flat sides of cam 32 to aline with arm 27 and release the shoe 30 of said arm from disc 17 whereby the disc was rotated through the gears 7 and 8 and shaft 9. The groove portions of cam 33 and 34 engaging the respective arms 28 and 29 forces their respective shoes into engagement with the discs 18 and 19 and maintains them stationary against rotation. At the second operation when arm 46 was alined with notch 48 the rotation of the arm 14 through seven spaces permits rotation of disc 18 and the alinement of notch 53 with notch 52 at point 60 in Figure 1. The groove portions of the cams 32 and

34 engaging the respective arms 27 and 29 forces their shoes 30 into engagement with their respective discs 17 and 19 and maintains them stationary while the arm 28 is in engagement with the flat portion of cam 33 and releases shoes 30 from disc 18. When arm 46 is moved to align with notch 49 the flat side of cam 34 is engaged by the resilient arm 29 to release the shoe 30 from disc 19 and thereby permit rotation of said disc while the grooved cam portion of cams 32 and 33 force the shoes 30 against the respective discs 17 and 18 and prevent rotation of these discs. By operation of the arm 14 through eleven spaces the notch 54 is caused to align with notches 52 and 53 at point 60 in Figure 1. In order to lock the device when the lug 55 is seated within the aligned notches 52, 53 and 54, the arm 14 is rotated anti-clockwise after the lugs 55 on the catch 2 are forced from their respective notches in the non-metallic discs and the end 56 of latch 2 is in position to prevent movement of the lock bolt 1 by its engagement with the lug 57. As has been noted actuation of handle 61 not only moves bolt 1 into its keeper but raises latch 2 through link 63.

When the arm 46 is moved to the notch #4, which is designated by the numeral 50, and the arm 14 is rotated in an anti-clockwise direction, the three discs 17, 18 and 19 are rotated simultaneously.

It will be noted that the combination for unlocking my permutation lock with reference to the three kinds of angular displacement of the arm 4 in cooperation with the movement of the crank arm 46 is 4 to 7 to 11. Any other combinations may be formed by the angular displacement of the metal discs 20 to the respective non-metallic discs 17, 18 and 19.

What I claim is:

1. In a permutation lock, a plurality of notched rotatable discs, means for causing rotation of said discs, and a resilient braking means for selectively preventing rotation of the discs, said braking means including a rotatable shaft, cams rigidly connected with the shaft, resilient arms in engagement with said cams, a spindle upon which the arms are pivotally mounted, said arms being provided with shoes adapted to be forced into engagement with the rotatable discs.

2. In a permutation lock, a plurality of notched rotatable members, means for rotating the members for alining the notches of said members, means for selectively locking said members against rotation, said selective

means comprising cam members having flat faces and an arcuately shaped face, means engaging the cams, and braking means adapted to be selectively forced in braking relation with one or more of the discs upon the rotation of the cams, a stop located adjacent the discs, and means projecting from the discs adapted to engage the stop for limiting rotation of the discs in one direction.

3. In a permutation lock, a plurality of notched rotatable discs, means for causing rotation of said discs, and a resilient braking means for selectively preventing rotation of the discs, said braking means including a rotatable shaft, cams rigidly connected with the shaft, resilient arms in engagement with said cams, a spindle upon which the arms are pivotally mounted, said arms being provided with shoes adapted to be forced into engagement with the rotatable discs, and means included in the rotatable means for angularly determining the rotation of the discs for alining the notches in said discs.

4. In a permutation lock, a plurality of notched rotatable discs, means for causing rotation of said discs, and a resilient braking means for selectively preventing rotation of the discs, said braking means including a rotatable shaft, cams rigidly connected with the shaft, resilient arms in engagement with said cams, a spindle upon which the arms are pivotally mounted, said arms being provided with shoes adapted to be forced into engagement with the rotatable discs, means included in the rotatable means for angularly determining the rotation of the discs for alining the notches in said discs, and a stop associated with the last mentioned means for predetermining the angular rotation of said means.

5. In a permutation lock, a plurality of non-metallic discs mounted for rotation, a braking means for selectively preventing rotation of said discs, means for causing angular rotation of the discs in accordance with the selective restraint by the braking means, means for causing selective operation of the braking means in accordance with the angular displacement of the discs by the rotatable means, said selective means comprising a plurality of cams on a shaft, each having flat faces and a curved face adapted to engage the braking means so that when the selective means is operated certain of the braking means will be placed in operative relation with the discs.

CHARLES FOSTER BLADES.
